UNITED STATES PATENT OFFICE.

VICTOR H. WHITING, OF NEW HAVEN, CONNECTICUT, ASSIGNOR TO SARGENT & COMPANY, OF NEW HAVEN, CONNECTICUT.

LOCK.

Application filed June 20, 1923. Serial No. 646,581.

To all whom it may concern:

Be it known that I, VICTOR H. WHITING, a citizen of the United States, residing in New Haven, county of New Haven, and 5 State of Connecticut, have invented certain new and useful Improvements in Locks, of which the following is a full, clear, and exact description.

This invention relates to locks, and more 10 particularly to a new and improved method for securing a lock in position in a door or door jamb.

When a lock is secured upon the outside of a door, it is necessary to secure it by some 15 means which may not be removed when the door is locked, to prevent the door being opened by an unauthorized person. Otherwise, the lock may be removed and the roll-back or other part of the lock mechanism 20 may be moved by the insertion of an instrument through the opening left by the removal of the lock case, and the door thus opened. This is especially true with locks applied to the doors of automobiles having 25 closed bodies, as the theft of cars of this character could often be prevented if the thief were not able to remove the lock from the outside of the door.

One object of my invention is to provide a 30 new and improved means of securing a lock case in position upon a door.

Another object of my invention is to provide means for securing a lock upon a door such that, while a lock may be applied to the 35 door with facility and without the expenditure of a great amount of labor, nevertheless, it will be impossible to remove it while the door is closed.

To these and other ends, the invention 40 consists in the novel features and combinations of parts to be hereinafter described and claimed.

In the accompanying drawings:

Fig. 1 is a front elevational view of an 45 automobile door having mounted thereon a lock embodying my improvements;

Fig. 2 is an edge view of the same;

Fig. 3 is a sectional view on line 3—3 of 50 Fig. 2;

Fig. 4 is a side elevational view of my improved lock structure;

Fig. 5 is a rear view of the same;

Fig. 6 is a sectional view on line 6—6 of 55 Fig. 5; and

Fig. 7 is a detail perspective view of the 55 dust cap spring.

While I have shown my improvements as applied to an automobile door, it will be readily understood that the invention is not limited to this application, but, on the other 60 hand, the improved lock mechanism shown is readily applicable to uses in other relations. In the drawings, I have shown, in a conventional way, an automobile body at 10 and the door at 11. The front edge 65 of the door is rabbeted by the provision of the shoulder 12 which is adapted to contact with a part of the door jamb to hold the door tightly closed. Upon the inner edge of the door, a latch case 13 is mounted, and 70 through the face plate of this case projects a latch bolt 14 which is adapted to be operated through suitable mechanism (not shown) by means of the handle 15.

The door may be locked in closed position in any suitable manner such as by dead locking the latch bolt 14, and to this end I have mounted from the outer face of the door a lock case 15^a provided with a spindle 16 which projects into the case 13 and may 75 there be suitably engaged with dogging mechanism for the latch bolt 14. It will be understood that, of course, if desired, a dead bolt may be mounted in the case 13 to be thrown by the rotation of the spindle 80 16. Where the spindle is used to throw a dead bolt or to dead lock the latch bolt illustrated, any common form of mechanism may be employed, and as such mechanism is well known in the art and does not 85 constitute a part of my invention, it is not necessary to illustrate it in detail.

The lock case 15^a may comprise a face plate 16^a, a cylinder 17 provided with a bore or opening in which is mounted a key barrel 95 18 and a pin tumbler extension 19, which is usually integrally formed with the cylinder 17. The pin tumbler extension 19 is flattened at the sides, as shown at 19^a and 19^b and is provided with a number of openings 100 or bores 20 in which are mounted the pin tumblers 21 which cooperate in the usual way with the pin tumblers 22 in the key barrel 18.

To the rear end of the key barrel 18 is 105 secured an extension 23 and to this extension is secured the spindle 16. The spindle may, if desired, be connected to the

- part 23, so as to have universal movement relatively thereto in order to correct for inaccuracies in mounting the latch case upon the door.
- 5 The face plate 16^a is usually provided with openings 24 for the reception of screws to secure the lock case in position upon the door. As these screws are accessible from the outside of the door, it will be 10 apparent that they may be easily removed, and, if the lock case is not secured by other means, the case itself may be removed and the door opened by any square instrument used in place of the spindle 16. To prevent 15 such removal of the lock, I have provided a rearwardly extending portion 25 upon the rear end of the pin tumbler extension 19, which is similar in cross section to the part 19 and forms a continuation thereof.
- 20 In order that a screw or the like may be passed through the edge of the door and engage the lock case so as to secure it in position, I provide the part 25 with a recess or opening 26 which is, in the form 25 shown, threaded so that the threaded end of the screw 27 may take therein. It will, of course, be understood that it may not always be necessary to thread the opening 26, for if the screw 27 is threaded into 30 the wood of the door, the mere entrance of the screw into the opening will prevent the removal of the lock, regardless of whether or not it has a threaded connection therewith. It will likewise be understood 35 that it will not always be necessary to form the opening 26 entirely through the part 25 of the lock case, but it may sometimes only be desirable to have a recess formed therein so that a shoulder will be provided 40 rearwardly of the screw 27 to engage the screw in case an attempt is made to withdraw the lock from the door. I find, however, that a screw entering an opening in the lock case in this manner holds the case 45 in position in the door positively and securely.
- The lock case is provided with a hinged dust cap 29, and a spring 30 is provided to hold the dust cap either in open position as shown in the figures of the drawing, 50 or in closed position when the key is removed from the key hole. The spring 30 is, in the form shown, a leaf spring turned or doubled so as to be substantially 55 U-shaped in form, its free end 31 being adapted to engage the edge 32 of a tail piece on the dust cap 29. When the dust cap is closed, the spring engages against the side 33 of the tail of the dust cap to 60 hold it in closed position. The other end of the spring is bent transversely to the body thereof, as shown at 34, and is inserted in a slot or kerf 35 in the front portion of the pin tumbler extension 19. It will 65 be apparent that the tension of the spring tends to hold the end 34 in position in the slot so that it does not need to be secured therein, and if the spring becomes broken, it is a comparatively easy task to remove it and replace it with another, without the use of any special tools.
- The dust cap 29 may be hinged to the lock case by having the tail piece thereof mounted in the notch 36 at the upper part 70 of the face plate 16^a and a pin 37 passed through the face plate and the tail piece.
- By providing the extension 25 upon the part of the lock case which contains the pin tumblers, I am enabled to arrange for the insertion of the screw 27 in the edge 80 of the door rearwardly of the shoulder 12 so that a shorter screw may be inserted. It will, of course, be evident that this extension may be made longer or shorter, as desired, without interfering in any way 85 with the position of the tumblers 21, so that no change of keys would be necessary when the lock is applied to doors of different thicknesses.
- While I have shown and described a preferred embodiment of my invention, it will be understood that it is not to be limited to all the details shown, but is capable of modification and variation within the spirit 90 of the invention and within the scope of the appended claims.
- What I claim is:
1. A cylinder lock adapted to be mounted in a door, said lock having a case provided with a recess, and a member inserted through the edge of the door and entering said recess to secure the lock in position. 100
  2. A lock case having a flattened portion and adapted to be mounted in a seat in a door, and a fastening screw secured in the door at right angles to the axis of the lock case, said flattened portion being provided with means to engage the rear side of the screw to hold the lock case in place. 105
  3. In combination with a door, a lock case mounted therein from one side thereof a fastening screw inserted into the edge of the door and arranged to have its end take into the lock case to secure the latter in place. 110
  4. In combination with a door, a lock case mounted therein from one side thereof, a fastening screw inserted into the edge of the door, and said lock case being provided with means to receive the end of said screw 115 to hold the lock in place.
  5. In combination with a door, a cylinder lock mounted therein having a pin tumbler extension and tumblers mounted in said extension, a screw inserted through the edge 120 of the door at right angles to the lock axis, said extension being provided with means to embrace the end of the screw to secure the lock in place. 125
  6. In combination with a door, a lock 130

- mounted on the face of the door provided with a lock case having a pin tumbler extension and tumblers mounted therein, said extension being provided with an opening 5 rearwardly of the tumblers and a fastening member inserted through the edge of the door and received in said opening.
7. In combination, a door, a lock mounted thereon, a transverse opening in said lock 10 case, and a fastening member inserted through the edge of the door and received in said opening to secure the lock in place.
8. In combination, a door, a lock case inserted therein from the face thereof, and 15 a member inserted through and secured in the edge of the door and having its end in engagement with the lock case to prevent the withdrawal thereof from the door in an axial direction.
9. In combination, a door having an opening in the face thereof, a lock case inserted axially in said opening, a fastening member inserted through and threaded in the 20 edge of the door, and means on the lock case disposed rearwardly of the fastening member to engage the end thereof and prevent removal of the lock case.
10. In combination, a door, a lock case 25
- mounted therein, said case being provided with a rearward extension, a fastening screw inserted through the edge of the door at right angles to the axis of the lock case and engaging said extension to secure the case in place.
11. In combination, a door, a lock case 30 mounted within an opening at one side of the door, said case being provided with a rearward extension, a fastening member secured in the door through the edge thereof, said extension being provided with an open- 35 ing to receive said fastening member.
12. In a door lock, a case provided with a pin tumbler extension, said extension being itself extended rearwardly and provided with a transversely disposed opening. 40
13. In a door lock, a case provided with a pin tumbler extension, said extension being itself extended rearwardly and provided with a transversely disposed opening, and a screw inserted through the edge of 45 the door in which the lock is mounted and adapted to take into said opening.

In witness whereof, I have hereunto set my hand this 4th day of June, 1923.

VICTOR H. WHITING.
